UNITED STATES PATENT OFFICE

STANLEY D. HARTSHORN, OF ST. DAVIDS, PENNSYLVANIA, ASSIGNOR TO PENNSYLVANIA CRUSHER COMPANY, OF NEW YORK, N. Y., A CORPORATION OF NEW YORK

APPARATUS FOR PREPARING COAL

Application filed March 28, 1929. Serial No. 350,704.

My invention relates to certain improvements in the operation of coal-breaking structures familiarly known as Bradford breakers, instances of modern type of such breakers being disclosed in the patents of Borton and 5 Hiller, and Hiller, Nos. 1,086,129, and 1,322,568, respectively, and in my companion application filed of even date herewith. The general manner of operating these breakers being well-known, it is unnecessary to refer to the same except in general terms. The coal to be reduced in size is introduced at one 10 end of the breaker, carried up by a series of shelves, and advanced by a series of deflectors. Any foreign material, in the form 15 of "tramp iron", sulfur balls, slate, etc., usually accompanying the coal, is delivered from the end of the breaker opposite the feed end, while the prepared coal passes through 20 apertures in the plates making up the wall of the breaker.

If the coal undergoing preparation is dry or comparatively so, little difficulty is experienced in the operation of breakers of this 25 type. If the coal is wet, however, the surface or free moisture present causes the "fines" accompanying the coal and found in practically all instances of bituminous coal intended for preparation by passage through a breaker 30 of this type to clog the apertures of the plates making up the walls of the breaker, and materially reduces the active portion of the same. In practice, it has frequently happened that two or more rows of plates will 35 become completely clogged during operation on wet coal containing "fines"; necessitating frequent stoppage for the purpose of removing this clogging material from the apertures of the breaker wall.

The object of my invention is to prevent 40 this clogging of the apertures in the walls of the breaker drum and to this end I propose to screen from the coal fed to the breaker drum substantially all of the "fines" accompanying the same. For this purpose I replace the usual feed chute with a movable 45 or vibrating screen, which screen receives the material from the car or other container and subjects it to a more or less violent shaking 50 operation for the purpose of removing the

"fines" therefrom. The fines so removed may be delivered to the same conveying means that serve to carry away the prepared coal which has passed through the apertured walls of the breaker.

Various forms of screens serving as feeding means, and various forms of mechanism for operating the same may be employed within the scope of my invention.

These and other features of my invention 60 are more fully described hereinafter; reference being had to the accompanying drawings, in which:

Figure 1 is a view in side elevation of a breaker of the Bradford type enclosed in 65 a housing usually employed in the use of the same; such view being partly in section on the line I—I, Fig. 2, and

Fig. 2 is an end elevation of the breaker structure and housing illustrated in Fig. 1, 70 looking in the direction of the arrow a, and partly broken away.

The breaker drum, which may be made up of end frames or spiders, 1, 1, longitudinal members 2, and a series of apertured 75 plates 3 connected to said longitudinal members and forming the wall (or walls) of such drum, is shown in Fig. 1 as mounted in a housing structure indicated generally at 5. Breaker structures of the Bradford type 80 are carried by stub shafts at each end; indicated at 6 in the present instance and forming trunnions which may be mounted in suitable bearings 7, supported by a suitable frame 8 which may also support the housing. 85 This arrangement leaves the end of the breaker structure substantially free except for the end frames or spiders, one of which is shown in section at 1, to which the longitudinal plate-supporting members 2 are secured. In 90 order that these breaker structures may be driven, one end of the same is provided with gear sections 9, annularly arranged, with a driving pinion (not shown) in engagement therewith.

At the feed end of the structure, instead of delivering the coal from the car or other container to a feed chute for passage to the interior of the drum, I interpose a suitable form of screen 12 which may be of the shake 100

type or any type to which motion of a suitable character may be applied that will insure such agitation of the material being introduced into the breaker as to free the same from the accompanying fines. In the present instance the screen is shown as pivotally mounted at 12^a. This motion may be more or less rapid, depending upon the exact character of the coal introduced, greater motion being probably required when the coal is particularly wet or contains an excessive amount of "fines".

In the present instance, I have shown leaf springs 13 having slotted ends supporting the screen, with a rotating eccentric member (or members) 14, driven in any suitable manner for the purpose of agitating the screen by lifting the same; the springs serving to effect return movement of the screen. The eccentric member (or members) 14 may be carried by a shaft 15 having a pulley wheel or other rotatable power transmitting member 16 connected by a belt or otherwise to a prime mover. Other forms of screens and other operating means are within the scope of my invention.

The coal to be broken with the accompanying "fines" is delivered from the car or other container to a hopper 17, which may be located directly above the screen 12; such screen being moved more or less rapidly depending upon the quantity of fines accompanying the coal. As a result of this operation, the coal delivered to the breaker is in lump size minus the fines and is, therefore, in better shape to be prepared by the normal operation of the breaker structure. As the entire body of fines has been removed from the lump coal prior to its entrance to the breaker, all danger of 40 the wet fines clogging the apertures of the plates making up the wall of the breaker is avoided.

Below the housing enclosing the breaker I may provide a conveyer of any usual type, indicated diagrammatically at 18, and the coal passing through the breaker may be received thereon. This housing is extended beneath the screen so that the "fines" removed from the coal subsequently passing to the breaker may be received on the same conveyer. It will be understood that the "fines" possess the same fuel value as the coal prepared in the breaker; the object in removing them from the coal subsequently broken being to increase the efficiency of the breaker by preventing the clogging of the apertures in the wall of the same through which the broken coal passes.

While I have illustrated and described certain specific forms of mechanism and an arrangement thereof intended to function for the desired purpose, it will be understood that I do not wish to be limited to the precise mechanism illustrated nor the exact manner of associating the parts employed for carry-

ing out the method or process of preparing coal constituting the subject of my invention.

I claim:

1. The combination with a rotating coal breaker of the Bradford type, of a movable screen over which the coal is delivered for passage to the breaker structure; said screen serving to remove the fines, means for imparting movement to said screen, and a housing for said breaker and screen extending beneath the latter and receiving the fines and broken coal.

2. The combination with a rotating coal breaker of the Bradford type, of an inclined screen over which the coal is delivered for passage to the breaker structure, means for agitating the screen; said screen serving to remove the fines, and a housing for said breaker and screen extending beneath the latter and receiving the fines and broken coal.

3. The combination with a rotating coal breaker, of a movable screen over which the coal is delivered for passage to the breaker structure; said screen serving to remove the fines, means for imparting motion to said screen, collecting means for said broken coal and fines, and a common receiver movable beneath said collecting means.

4. The combination of a rotating coal breaker of the Bradford type, a vibrating screen disposed ahead of such breaker and over which the coal is delivered for passage thereto; said screen serving to remove the fines, means for imparting motion to said screen, means for imparting rotative movement to said breaker, and a housing for breaker and screen extending beneath the latter and receiving the fines and broken coal.

5. The combination with a rotating coal breaker of the Bradford type having apertured plates through which prepared and sized coal may be discharged, of a screen for the removal of fines from such coal prior to its delivery into the breaking chamber, means for agitating said screen during passage of the coal, and common means for carrying off the fines and the prepared coal delivered from the breaker structure.

6. The combination with a rotating coal breaker of the Bradford type having apertured plates through which coal prepared and sized by breaking may be discharged, of a screen for the removal of fines from such coal prior to its delivery into the breaking chamber, means for agitating said screen during passage of the coal over the same, a common conveyer belt for carrying off the fines and prepared coal, and separate chutes for delivering the broken coal and fines to said belt.

In witness whereof I have signed this specification.

STANLEY D. HARTSHORN. 130
